Patented Feb. 12, 1918.

FIG. 1.

FIG. 2.

INVENTOR.
G. H. AKERLUND.
BY HIS ATTORNEY:
A. M. Carlsen.

UNITED STATES PATENT OFFICE.

GUSTAF H. AKERLUND, OF BRAY, MINNESOTA.

RAZOR-WIPING ATTACHMENT FOR SHAVING-MUGS.

1,256,282.

Specification of Letters Patent. Patented Feb. 12, 1918.

Application filed February 5, 1917. Serial No. 146,631.

To all whom it may concern:

Be it known that I, GUSTAF H. AKERLUND, a citizen of the United States, residing at Bray, in the county of Pennington and State 5 of Minnesota, have invented a new and useful Razor-Wiping Attachment for Shaving-Mugs, of which the following is a specification.

My invention relates to shaving mugs, 10 and the object is to provide a shaving mug with means for removing the lather from the razor without the use of paper, cloth or similar wiping devices. Another object is to make the new razor cleaning device an 15 attachment to any ordinary shaving mug.

In the accompanying drawing, Figure 1 is an elevation of a shaving mug with my device clamped to one side, and showing a 20 razor placed in position to be cleaned. Fig. 2 is a sectional elevation on the line 2—2 in Fig. 1.

Referring to the drawing by reference numerals, 1 designates an ordinary shaving mug made of china-ware or other glazed 25 crockery or of metal; and, the cleaning device, consisting of a plate 3^a, is secured to the edge of the mug by the clamping member 8, having a thumb screw 9 the tightening of which will clamp the plate to the 30 mug. The plate 3^a is provided with a notch,

forming two cleaning edges 5 and 5^a so close together that when a razor 6 is drawn between them it will touch both of them simultaneously and thus clean both sides of it at one time. At the lower edge of the notch 35 is provided a clearing 3^b the object of which is to save the fine edge of the razor from direct contact with the cleaning plate 3^a.

In the use of the device, the lather is prepared in the mug in the usual manner by 40 a brush (not shown) and is then applied to the face preparatory to shaving. Hair and lather then accumulate on the razor which is drawn between the edges 5 and 5^a of the cleaning plate, and thus removes the lather 45 which falls back into the cup or into a special compartment in the cup. The plate 3^a may be made of sheet metal, aluminum, copper, rubber or any other suitable material. 50

What I claim is:

A razor cleaning device comprising a plate with an aperture in it and a V-shaped notch extending with its point into the aperture, the edges of said notch being 55 curved so as to fit the opposite sides of a hollow-ground razor.

In testimony whereof I affix my signature.

GUSTAF H. AKERLUND.
